UNITED STATES PATENT OFFICE

2,604,187

METHOD AND APPARATUS FOR SUPPRESSING STEAM AND DUST RISING FROM COKE BEING QUENCHED

Morton I. Dorfan, Pittsburgh, Pa.

Application June 8, 1951, Serial No. 230,597

12 Claims. (Cl. 183—46)

1

This invention relates to the quenching of hot coke immediately after it leaves a coke oven, and more particularly to the control and disposition of the steam and dust produced while the coke is being quenched.

In the process of making coke, the red-hot coke is pushed from by-product coke ovens into cars which then are moved through the lower part of quenching towers. While the cars are in the towers the coke is flooded with water to quench it. A great quantity of water is used for this purpose, with the result that a great amount of steam rises from the coke and carries with it coke dust. The steam contains, among other things, poisonous phenols which pollute the atmosphere, and the water vapor forming the steam has been lost. Up to the present the coke dust produced during quenching not only has been lost, but it also has created a great nuisance in the community.

It is among the objects of this invention to provide a method and apparatus for treating the dust and steam rising from coke being quenched which confines them to the quenching tower, which salvages the dust and a large part of the water that formed the steam, which keeps the dust and phenols in the steam from polluting the atmosphere, which uses coke as a filtering medium, which salvages the filtering medium, and which is simple in construction and operation.

In accordance with this invention my steam and dust suppressing apparatus is associated with a coke quenching tower, through the lower portion of which cars of hot coke travel so that the coke therein can be cooled by water. The apparatus includes an exhaust fan for drawing the steam and dust up into the tower, and a chute extending from the top of the tower down to a point above the level of the coke cars. Filtering coke is delivered to the upper end of the chute to keep it full, and means is provided for controlling release of the coke from the lower end of the chute. The chute has perforated side walls and a plurality of longitudinally spaced sections. Provision is made in the tower for directing the upward flow of steam and dust transversely through each of the chute sections in succession, whereby the flow passes back and forth through the coke in the chute, which thereby serves to filter out the dust. To condense the steam in the tower, water is sprayed through a perforated side wall of one of the chute sections onto the coke in that section. The steam entering the section of wet coke is condensed

therein. The spray water and condensed steam that run out of the side of the chute may be collected in a drain pan and returned to a sump for re-use. Coke in the chute is periodically or continuously released from the lower end of the chute onto the quenched coke in the car below it, whereby the filtering medium is continually being renewed and none of it is lost. Preferably, two chutes are used and extend diagonally down through the tower.

The preferred embodiment of the invention is illustrated in the accompanying drawings, in which Fig. 1 is a plan view of a quenching tower incorporating my invention; Fig. 2 is a side view of the tower with parts broken away; Fig. 3 is an end view with most of the tower end wall removed and parts of the suppressing apparatus shown in section; and Fig. 4 is an enlarged detail of one of the supports for the chute side walls.

Referring to the drawings, a conventional masonry coke quenching tower 1 is shown for the purpose of illustration. The tower has end walls 2, the lower portions of which are open to provide ports 3 through which cars 4 of hot coke can travel on rails 5. The tower is long enough to accommodate at least one car, and the top of the tower is open. In the lower part of the tower above the level of the car ports are the usual pipes 6 for spraying coke in the cars with water to quench it. While the coke is being quenched, a great deal of steam is produced, and the steam carries dust and poisonous phenols up through the tower. Heretofore, the dust and steam have left the top of the tower and spread out over the surrounding territory, thereby creating a great nuisance and a considerable amount of damage as well as loss of the dust and the water that produced the steam. It is a feature of this invention that such dust and steam are suppressed within the tower before they can leave it.

Accordingly, apparatus is associated with the tower for condensing the steam and for filtering out the coke dust. Starting at the top, the apparatus includes motor driven blowers or exhaust fans 7 mounted on top of the tower with their inlets connected by large elbows 8 to the tops of exhaust hoods 9 closing the upper part of the tower. These fans draw a strong current of air in through the car ports 3 and up through the tower. The rising current of air carries the steam and coke dust upward with it. However, the dust and steam do not reach the fans to be discharged into the atmosphere, because the

steam is condensed and the dust is filtered out of the air before they reach the top of the tower. For this purpose a filtering bed or curtain of filtering coke is conducted down through the tower in such a way that the rising dust and steam have to pass back and forth through it. The filtering coke may be coke of any size suitable for use as a filter medium, suitable examples being coke $\frac{3}{8}'' \times \frac{5}{8}''$, $\frac{1}{2}'' \times 1''$ or $1\frac{1}{2}'' \times 2\frac{1}{2}''$.

The filtering coke flows down through perforated conduit means, preferably in the form of two independent chutes extending the full length of the tower. As shown in Fig. 3, each chute extends diagonally back and forth down between the opposite sides of the tower from a point near the top of a side wall to a point at the center of the tower a short distance above the level of the car ports. Thus, the chute has a plurality of inclined sections. Three of these longitudinally spaced sections for each chute are generally considered to be enough, but more sections can be used if desired. The sections of one chute are inclined in directions opposite to the sections of the other chute, so that the lower ends of the upper pair of sections 12 meet at the center of the tower and empty into the upper ends of the middle pair of sections 13. The lower ends of the middle pair of sections engage the side walls of the tower, and the lower ends of the lowest pair of sections 14 meet at the center of the tower and deliver to the upper ends of a pair of short parallel sections 16. The lower ends of these parallel sections normally are closed by a trough-like valve 17 that extends lengthwise of the tower and is pivotally supported at its opposite ends. One trunnion 18 (Fig. 2) of the valve may extend through an end wall of the tower and be provided with a suitable lever 19 for turning it in order to swing the valve to either side.

Communicating with the top of each chute is a pair of upwardly tapered equalizing chutes 21, the upper ends of which are connected to the outlets of a pair of vertical elevating conveyors 22 of any suitable construction mounted outside of the tower. The lower end of each conveyor is housed in a bin 23, to which filtering coke can be supplied in any suitable manner. The coke is lifted from the bins by the conveyors and delivered to the upper ends of the chutes at a rate sufficient to maintain the chutes substantially filled with coke 24. Consequently, the space inside the tower is crossed at three different levels by curtains of filtering material.

The opposite side walls of each chute are perforated to permit the air and steam and dust to flow transversely through the three pairs of inclined chute sections and the filtering coke inside of them. To keep the filtering coke from falling through the perforations, each chute side wall preferably is formed from a plurality of metal plates 26 which extend lengthwise of the tower. The plates forming each side wall are disposed in laterally spaced overlapping relation, with the upper part of each plate at the outside of the lower part of the plate above it. Therefore, the slots that are formed between the plates have lower ends inside the chute, so that filtering coke can not fall out of the slots. Preferably, each plate is in the form of a flattened Z, with the upper portions of each opposed pair of plates of a chute substantially parallel and connected by downwardly converging portions to substantially parallel lower portions disposed between the upper portions of the next lower pair of plates. The two side walls of each chute

diverge gradually from top to bottom of the chute to accommodate the increase in volume of coke in the chute as it moves downward, due to the added coke dust picked up by the filtering coke. The plates may be supported in the tower in any suitable manner. One way of doing it is to insert their ends in recesses 27 (Fig. 4) formed in the faces of inclined supporting members 28 anchored to the end walls of the tower and to the side walls between the end walls. Extending downward from the bottom of each recess is a slot 29 that snugly receives the lower portion of a plate 26 to hold it in place. The central supports act as partitions which divide each chute into two portions, each of which is fed by one of the conveyors.

With car 4 in the bottom of the tower loaded with hot coke and the chutes full of filtering coke 24, the fans 7 draw up through the tower air laden with the steam and dust given off by the coke being quenched by water from pipes 6. The flow is inward through the lower pair of chute sections 14 which form the primary filter stage that removes most of the dust. Most of the steam and the rest of the dust then flow outward through the central pair of chute sections 13, in which the steam is condensed by water which is sprayed down onto the coke flowing through those sections from pipes 30 extending lengthwise through the tower. More of the dust also is removed in passing through the wet coke, which acts as an excellent filter. Some of the steam also was condensed in flowing through the saturated coke that had moved down into the lowest pair of inclined sections of the chutes. The dust remaining in the rising air current is trapped by the filtering coke in the upper pair of chute sections 12 as the air is drawn inward through them just before it enters the exhaust hoods. This last stage of the filter also takes out most of the water vapor entrained in the air by reason of the condensation of the steam. By having a plurality of filter sections, the overall efficiency of the filter in filtering out solids is greatly increased. The filtering and condensing accomplished by this apparatus also confines the poisons and acids in the steam to the tower.

Much of the water that is sprayed on the filtering coke in the second stage of the filter, as well as the condensed steam, drain out through the slots in the sides of the chutes before the water and condensate reach the valve 17 at the bottom of the chutes. This water and the coke dust that it washes out of the chutes with it are caught by pans 31 extending from the side walls of the tower inward toward the valve. These pans can be connected with a sump (not shown) outside of the tower, into which the dust laden water is drained for collection of the dust and re-use of the water.

In order to continually renew the filter bed so that it will not become clogged with coke dust, the filtering coke is released from the bottom of the chutes by opening valve 17. The released coke falls onto the load of quenched coke below it, so that the used filtering coke and the coke dust mixed with it are not lost. This arrangement also provides a convenient way of disposing of the used filtering coke and dust. Although it is possible to feed the filtering coke continuously through the chutes, it is preferred to move it intermittently through them by opening the bottom valve periodically. For example, in one coke quenching installation, 100 gallons of water

per ton of coke are sprayed on the coke to quench it, and the quenching period is 90 seconds long. The filtering coke is dropped from the chutes onto the quenched coke in a car below it at a rate of $\frac{1}{2}$ to 1 foot of fall per minute for a period of one minute during the middle minute of the 90 second quenching period. The conveyors 22 can be operated continuously or intermittently, just so they keep the chutes full of filtering coke.

By using as a filter the same kind of material as that from which the steam and dust rise, the filtering material can be salvaged and mixed with the pay load. This apparatus is relatively simple, yet very efficient and easy to operate. Its use eliminates a public nuisance that has been suffered for many years. In addition, it salvages dust and water that formerly were lost during coke quenching.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. The combination with a coke quenching tower through the lower portion of which cars of coke travel so that the coke therein can be quenched by water, of apparatus for suppressing the steam and dust rising into the tower from the coke being quenched, said apparatus comprising an exhaust fan for drawing said steam and dust up into the tower, a chute extending from the top of the tower down to a point above the level of said cars, means for delivering filtering coke to the upper end of the chute, means for controlling release of filtering coke from the lower end of the chute, the chute having perforated side walls and a plurality of longitudinally spaced sections, means for spraying water through a perforated side wall of one of said sections onto the coke therein, and means directing the upward flow of steam and dust transversely through each of said sections in succession, whereby said dust will be filtered out by the filtering coke and said steam will be condensed in passing through said one section.

2. The combination with a coke quenching tower through the lower portion of which cars of coke travel so that the coke therein can be quenched by water, of apparatus for suppressing the steam and dust rising into the tower from the coke being quenched, said apparatus comprising an exhaust fan for drawing said steam and dust up into the tower, a chute extending from the top of the tower down to a point above the level of said cars, means for delivering filtering coke to the upper end of the chute at a rate to maintain the chute filled, means for controlling release of filtering coke from the lower end of the chute, the chute having perforated side walls and a plurality of longitudinally spaced sections, means for spraying water through a perforated side wall of a chute section above the lowest section and onto the coke therein, and means directing the upward flow of steam and dust transversely through each of said sections in succession, whereby said dust will be filtered out by the filtering coke and said steam will be condensed in passing through said one section.

3. The combination with a coke quenching

tower through the lower portion of which cars of coke travel so that the coke therein can be quenched by water, of apparatus for suppressing the steam and dust rising into the tower from the coke being quenched, said apparatus comprising an exhaust fan for drawing said steam and dust up into the tower, a chute extending from the top of the tower down to a point above the level of said cars, means for delivering filtering coke to the upper end of the chute at a rate to maintain the chute filled, means for controlling release of filtering coke from the lower end of the chute, the chute having perforated side walls and three longitudinally spaced sections, means for spraying water through a perforated side wall of the center section onto the coke therein, and means directing the upward flow of steam and dust transversely through each of said sections in succession, whereby said dust will be filtered out by the filtering coke and said steam will be condensed in said center section of the chute.

4. The combination with a coke quenching tower through the lower portion of which cars of coke travel so that the coke therein can be quenched by water, of apparatus for suppressing the steam and dust rising into the tower from the coke being quenched, said apparatus comprising an exhaust fan for drawing said steam and dust up into the tower, a chute extending from the top of the tower down to a point above the level of said cars, means for delivering filtering coke to the upper end of the chute at a rate to maintain the chute filled, means for controlling release of filtering coke from the lower end of the chute, the chute having perforated side walls and a plurality of longitudinally spaced sections, means for spraying water through a perforated side wall of one of said sections onto the coke therein, means directing the upward flow of steam and dust transversely through each of said sections in succession, whereby said dust will be filtered out by the filtering coke and said steam will be condensed in passing through said one section, and a drain pan located near the bottom of the chute for catching spray water and condensed steam and conducting it away.

5. The combination with a coke quenching tower through the lower portion of which cars of coke travel so that the coke therein can be quenched by water, of apparatus for suppressing the steam and dust rising into the tower from the coke being quenched, said apparatus comprising a chute extending diagonally back and forth down between opposite sides of the tower from its top to a point above the level of said cars, whereby the chute has a plurality of inclined sections, means for delivering filtering coke to the upper end of the chute at a rate to maintain the chute filled, means for controlling release of filtering coke from the lower end of the chute, the chute having perforated side walls, an exhaust fan for drawing steam and dust up into the tower and transversely through each of said inclined chute sections in succession, and means for spraying water down onto a chute section above the lowest one to wet the coke therein to cause condensation of steam passing therethrough.

6. The combination with a coke quenching tower through the lower portion of which cars of coke travel so that the coke therein can be quenched by water, of apparatus for suppressing the steam and dust rising into the tower from the coke being quenched, said apparatus com-

75

prising an exhaust fan for drawing said steam and dust up into the tower, a chute extending from the top of the tower down to a point above the level of said cars and having a plurality of longitudinally spaced sections, means for delivering filtering coke to the upper end of the chute, means for controlling release of filtering coke from the lower end of the chute, the major portion of the chute being formed from pairs of laterally spaced plates extending lengthwise of the tower with the upper portions of each pair spaced apart farther than their lower portions for receiving the lower portions of the next higher pair of plates, each pair of plates being spaced from the plates that it extends between to provide slots in the side walls of the chute, and means directing the upward flow of steam and dust transversely through the slots of each of said chute sections in succession.

7. The combination with a coke quenching tower through the lower portion of which cars of coke travel so that the coke therein can be quenched by water, of apparatus for suppressing the steam and dust rising into the tower from the coke being quenched, said apparatus comprising a chute extending diagonally back and forth down between opposite sides of the tower from its top to a point above the level of said cars, whereby the chute has a plurality of inclined sections, a second chute shaped substantially the same as the first-mentioned chute but having its inclined sections inclined in directions opposite to the inclined sections of the first chute, the inclined sections of each chute extending from the adjoining side wall of the tower to the other chute at about the center of the tower, the lower ends of the chutes coming together, means for delivering filtering coke to the upper ends of the chutes at a rate to maintain them filled, means for controlling release of filtering coke from the lower ends of the chutes, the chutes having perforated side walls, and an exhaust fan for drawing steam and dust up into the tower and transversely through each pair of opposed chute sections in succession.

8. The combination with a coke quenching tower through the lower portion of which cars of coke travel so that the coke therein can be quenched by water, of apparatus for suppressing the steam and dust rising into the tower from the coke being quenched, said apparatus comprising a pair of chutes converging downward from the opposite sides of the tower near its top to a meeting point at the center of the tower and then diverging downward to the sides of the tower and then converging downward again to a meeting point at the center of the tower above the level of said cars, the lower ends of the chutes extending downward a short distance from said last-mentioned point, a valve normally closing the lower ends of the chutes, means for delivering filtering coke to the upper ends of the chutes to maintain them filled, the chutes having perforated side walls, an exhaust fan for drawing steam and dust up into the tower and transversely through the inclined portions of the chutes in succession, and means for spraying water on the coke in the chutes.

9. The combination with a coke quenching tower through the lower portion of which cars

of coke travel so that the coke therein can be quenched by water, of apparatus for suppressing the steam and dust rising into the tower from the coke being quenched, said apparatus comprising a pair of chutes converging downward from the opposite sides of the tower near its top to a meeting point at the center of the tower and then diverging downward to the sides of the tower and then converging downward again to a meeting point at the center of the tower above the level of said cars, the lower ends of the chutes extending downward a short distance from said last-mentioned point, a valve normally closing the lower ends of the chutes, means for delivering filtering coke to the upper ends of the chutes to maintain them filled, the chutes having perforated side walls, an exhaust fan for drawing steam and dust up into the tower and transversely through the inclined portions of the chutes in succession, means for spraying water on the coke in said diverging sections of the chutes, and drain pans below the lower converging sections of the chutes for catching water and condensed steam.

10. The method of suppressing steam and dust rising from a mass of coke being quenched, comprising conducting the steam and dust transversely through longitudinally spaced sections of a curtain of filtering coke in succession to filter out the dust, spraying water on one of said sections to condense the steam, withdrawing coke from one end of the curtain, and adding coke to the opposite end of the curtain.

11. The method of suppressing steam and dust rising from a mass of coke being quenched, comprising drawing the steam and dust transversely through vertically spaced sections of a curtain of filtering coke in succession to filter out the dust, spraying water on the curtain section next to the one closest to the source of said steam and dust, whereby to condense steam in the sprayed section, withdrawing coke from the lower end of the curtain, and adding coke to the upper end of the curtain.

12. The method of suppressing steam and dust rising from a mass of coke being quenched, comprising drawing the steam and dust transversely through three vertically spaced sections of a curtain of filtering coke in succession to filter out the dust, spraying water on the middle section of the curtain to condense the steam, withdrawing coke from the lower end of the curtain and depositing it on said mass of coke, and adding coke to the upper end of the curtain at a rate to maintain the curtain.
